TREAT T. PROSSER, OF CHICAGO, ILLINOIS.

Letters Patent No. 88,981, dated April 13, 1869.

IMPROVEMENT IN MACHINES FOR HEADING BOLTS.

The Schedule referred to in these Letters Patent and making part of the same.

To all whom it may concern:

Be it known I, that TREAT T. PROSSER, of Chicago, in the county of Cook, and State of Illinois, have invented certain new and useful Improvements in Machines for Heading Bolts and Forging Nuts; and I do hereby declare that the following is a full, clear, and exact description thereof, reference being had to the accompanying drawings, making part of this specification, and to the letters of reference marked thereon, like letters indicating like parts, wherever they occur.

To enable others skilled in the art to construct and use my invention, I will proceed to describe it.

My invention consists in a novel construction of a machine for heading bolts, and also for forging, or shaping nuts, as hereinafter explained.

Figure 1 is a side elevation of the machine complete, with a portion broken away, for the purpose of more clearly exhibiting the parts.

Figure 2 is a transverse section, taken on the line *x-x* of fig. 1, looking from above downward.

Figure 3 is a plan view, looking from below, of a portion detached.

Figure 4 is a transverse section of the same, taken on the line *y-y* of fig. 3; and

Figures 5, 6, 7, and 8 are views of portions shown detached, and more in detail.

In constructing my machine, I first provide a platform, or base *A*, fig. 1, which may consist of a cast-iron circular bed-plate, having a vertical flange, or simply feet projecting downward, and resting on the floor, thus raising the bed-plate proper high enough to permit some of the devices to work underneath the same, as shown in fig. 1.

Upon this base I mount two strong posts *B*, and on them, a short distance above the base, I secure a strong plate, *C*, which has four arms *K* projecting radially from its centre, this plate serving the threefold purpose of a guide for the hammer, and, with its arms *K*, a guide for the dies and a support for a portion of the operating mechanism.

Still above this plate *C*, I mount, on the posts *B*, another strong plate *D*, which serves as a guide for the upper portion of the hammer *H*, and also as a support to a vertically-projecting arm, *F*, on two opposite sides, which arms serve, at their upper ends, as bearings for vertical shafts *I*, as represented in fig. 1.

At the top of the posts *B*, I place another plate *R*, which forms a bearing for the main driving-shaft *J*.

Upon the base *A*, I place a circular bed, or anvil *T*, which is journaled on one of the posts *B*, which passes through a hole at its centre, so that said plate *T* rotates around said post *B*, the plate, or anvil *T* being of such a diameter that it will reach a little beyond the centre of the bed *A*, or nearly to the other post *B*, as shown clearly in fig. 2, this plate *T* being provided with teeth on its periphery, for imparting motion to it, as hereinafter explained.

At the extremity of each of the four arms *K* of the

plate *C*, is located a vertical shaft *b*, carrying an eccentric, *M*, (see fig. 2,) which is connected by a strap, or yoke *m*, to a die, *P*, by means of a pivot, *a*, the rear end, or arm *t* of these dies being formed dovetailed, as represented in fig. 5, so as to work in a corresponding groove in the under side of the arms *K*, and thereby guide the dies, and cause them to work in a straight line, to and fro, when operated by the eccentrics *M*, the eccentrics being so arranged in pairs as to cause the dies, which stand directly opposite each, to advance or recede simultaneously, first one and then the other pair moving alternately, as shown in fig. 2.

In the plate, or anvil *T*, a series of holes is made, to receive and hold a couple of standing dies, or jaws *i* and *i'*, having a recess formed in their adjoining faces, so that when placed together they will serve to receive and hold the bolt to be headed, the jaw *i'* having an arm projecting outwardly, as shown in figs. 1 and 2, which arm, as the plate *T* revolves and brings it under the hammer, strikes against an eccentric *g*, secured to the opposite post *B*, which thereby presses the jaw *i'* inward, and thus clasps and holds the bolt, or spike firmly between it and the jaw *i*, while being operated upon by the dies *P* and the hammer *H*, the jaw *i'* being released the moment it passes the eccentric *g*.

The eccentric is made adjustable on the post *B*, so that by turning it thereon it may be made to press against the jaw *i'*, with more or less force, as may be required, and as shown in fig. 1.

The hammer consists of a plunger, or weight *H*, working vertically in holes in the centre of the plates *C* and *D*, and is operated by a pitman, *E*, connected to a crank (shown in red lines) on the driving-shaft *J*, the pitman *E* being connected to the hammer *H* by a sliding stem, working in the upper end of the hammer, to insure a dead stroke, or blow, as is customary in this class of hammers.

Motion is transmitted to the dies *P* and the rotating-plate, or anvil *T*, by means of two vertical shafts *I*, standing opposite each other, and each being driven by a bevel-gear, *l*, at its upper end, which engages with a similar gear-wheel *p*, on the opposite ends of the main, or driving-shaft *J*.

Each of these shafts *I* has mounted on it a spur-gear wheel *I'*, at such a position as to gear into corresponding wheels *L*, secured to the shafts *b*, by which the latter are caused to rotate, carrying with them the eccentrics *M*, and thereby operating the dies *P*.

On one of the shafts *I* there is also secured, at its lower end, just above the base *A*, a pinion, *c*, fig. 1, which gears into another pinion *h*, which, in turn, gears into a toothed ring, *Q*, which fits into a recess on the under side of plate *T*, as shown clearly in fig. 2, this ring *Q* being of the same external diameter as the plate *T*, and its teeth coming out flush with the teeth of the plate *T*, as represented in figs. 1 and 2.

Loosely upon the shaft *I*, and just over the pinion

e, is mounted another pinion *b'*, which is provided, on its upper side, with a hub, *f*, having two notches formed in it, to receive a key, *a*, which is secured rigidly to a rod, *e*, which extends from the end of a spring-arm, *u*, up through the base *A*, and up into the lower portion of shaft *I*, which is made hollow to receive it, and which also has a slot formed in it, to permit the key *a* to move up and down with the rod *e*, so as to engage with the notches of the hub *f*, and be released from the same, at intervals, as required—the key *a* and the notched hub *f* thus forming a clutch, by which the pinion *b'* is caused to rotate with the shaft *I*, when the key and hub engage, or is permitted to remain stationary when they are disengaged.

Another pinion *d* is mounted on a stud, in such a position as to gear on one side into the loose pinion *b'*, and on the other side into the teeth of plate *T*, whereby the latter is caused to rotate whenever the key *a* engages with the hub of the loose pulley *b'*, and to remain stationary whenever they are disengaged.

The plate *T* is intended to remain stationary long enough to permit the head to be formed, by the joint operation of the hammer and the dies.

In order to effect this, I secure to the under side of the base *A* the spring-arm *u*, to the end of which is attached the sliding-rod *e* that raises and lowers the key *a*, as previously described; and to this arm *u* I also attach two bolts, or pins *r* and *s*, the first of which has its point bearing in a groove, *o*, formed in the under side of the ring *Q*, while the latter has its point engaging in holes *k*, in the under face of plate *T*, as shown in fig. 3.

The groove *o*, as represented in fig. 3, does not extend entirely around, but a portion of the ring *l* is left without any groove, so that when that portion of the ring comes over the pin *r*, it throws down the arm *u*, thereby withdrawing the pin *S* from the hole *k* in the plate *T*, and at the same time draws down the rod *e*, and causes the key *a* to engage with the hub *f* of pinion *b'*, by which the plate *T* is rotated until the next hole *k* comes over the pin *S*, which again locks the plate *T*, and holds it in position while a head is formed, as before.

It will thus be seen that while the ring *Q* is continuously in motion, the plate *T* moves only at intervals, which are regulated by the comparative speed of the two, or by the number of times the arm *u* shall be operated by the cams *l* on the face of the ring *Q*, of which there may, of course, be any desired number.

In the present instance I have represented four sets of holding dies *i* and *i'*, and have, therefore, arranged the parts so as to give to the plate *T* a quarter revolution at each movement.

The bolt to be headed is dropped into position between the jaws *i* and *i'*, when the plate *T* is stationary, and at that point which is nearest the outside of the machine.

As the plate *T* rotates, it carries the bolt around under the hammer *H*, where it remains (the plate stopping so as to hold it at that point) while the dies *P* press its head alternately on opposite sides, and the hammer hits it a blow on the top, the strokes of the hammer and the pressures of the dies being equal in number.

As the plate *T* rotates, it brings at each movement a finished bolt, around from under the hammer, to near the point where the operator stands, and where it is thrown out by a follower, *n*, which works loosely in the hole between the jaws *i* and *i'*, which is forced suddenly upward by a bolt, *n'*, attached to a spring-arm, *W*, also located within the hollow base *A*, as shown in figs. 4 and 8.

The point of the bolt *n'* rests in a groove *v*, fig. 3, which groove is arranged to pass under the jaws that hold the bolt, and is so inclined on the side opposite that at which the bolt *n'* enters the recess, that as soon

as the plate *T* commences to revolve the bolt is forced down, thereby bringing on the arm *W* a pressure, or tension that serves to force the bolt *n'* suddenly against the bottom of the follower *n*, as soon as the plate has turned far enough to bring the latter over the former, as shown in fig. 8, which is a section on the line *z-z* of fig. 3.

By this means each bolt is forced suddenly out of the recess, as it is brought around to the proper point, the operator at the same time supplying the recess in front with a fresh bolt to be operated upon.

The machine may be so geared as to strike any required number of blows upon each head, there being eight blows of the hammer and eight strokes of each pair of dies in the present case.

It is also obvious that the rotating plate, or anvil *T* may be provided with any desired number of recesses for receiving and holding the bolts, the cam *l* on the ring *Q* being arranged to so operate the clutch-rod *e* and the locking-pin *S* as to correspond therewith.

The dies *P* may have their points so recessed as to permit the insertion or removal of dies of special forms and sizes, as represented by *z*, fig. 5, so as to adapt the machine to the forming of heads of any desired form or size.

By forming the face of the dies *P*, and arranging them to overlap, as represented in fig. 6, it will be seen that a round head may be formed without leaving any fin, or projecting points thereon; and by forming the face of the hammer concave, as represented in section in fig. 7, the top of the head may be rounded more or less, as may be desired, and thus the head be finished complete, with the exception of polishing them, in those cases where it is desired to do so.

By this machine, nuts may likewise be formed as readily as bolt-heads, and that, too, without any change in the machine.

To do this, the nuts, or rough blanks should first be punched with a hole of the requisite size, and then slipped on to the end of an arbor of proper size and length, to fit between the clamping-jaws *i* and *i'*, when it is inserted and operated upon the same as a bolt, the arbor in this case simply taking the place of the body of the bolt, and serving to hold the nut in place, and also to prevent the hole in it from being obliterated or distorted.

By using an arbor that has a screw thread cut on it at the point where the nut is put on, and then having the dies *P* compress the nut, the thread will be formed in the nut at the same operation.

By this construction I am able to produce a machine that performs its work in a very efficient manner, producing a superior article, and that performs its work automatically and rapidly.

Having thus described my invention,

What I claim, is—

1. As an improvement in bolt-heading machines, the hammer *H*, the pressing dies *P*, and the rotating-anvil, or table *T*, when said parts are constructed and arranged to operate substantially as and for the purpose set forth.

2. The rotating-table *T*, with the clamping-jaws *i* and *i'*, arranged to operate in connection with the adjustable eccentric *g*, substantially as and for the purpose described.

3. The curved dies *P*, in combination with the rotating-table *T*, when said parts are constructed and arranged as described, to permit the blanks to be carried around under the dies, and brought to the required position for being operated upon, and then moved to the point of discharge, as set forth.

4. The combination of the table *T*, ring *Q*, and the spring-arm *u*, with the bolts *s*, *r*, and *e* attached thereto, with the gear-wheels *d*, *c*, *h*, and *b* all arranged to operate substantially as described.

5. The arrangement of the spring-arm *W* with its pin

n', operating in connection with the inclined grooves *v* in the under side of the table *T*, for ejecting the finished bolts, substantially as described.

6. The arrangement of the shaft *J* with its crank and bevel-gear *p*, the shafts *I*, with the wheels *l* and *I'*, and the shafts *b*, with the wheels *L* and eccentrics *M*, all substantially as herein described, for the pur-

pose of operating the hammer *H* and the dies *P*, as and for the purpose set forth.

T. T. PROSSER.
